TENS TRANSFER MECHANISM

Max Garbell, Chicago, Ill., assignor to Victor
Adding Machine Company, Chicago, Ill., a cor-
poration of Illinois

Original application March 24, 1934, Serial No.
717,156. Divided and this application Novem-
ber 17, 1934, Serial No. 753,449

6 Claims. (Cl. 235—133)

This invention relates to improvements in adding and recording machines and more particularly to transfer mechanism coacting with the totalizer in which adding and subtracting operations are carried out during the totaling and listing operations of the machine.

The chief objects of the invention are the provision of novel and efficient mechanism for accumulating totals or subtracting given amounts which includes new and improved totalizer units operable by direct engagement with the type bars or rack bars of an adding machine and having means coacting therewith and positively operated thereby to effect a transfer from one unit to another throughout the whole width of the machine when such functioning is necessary.

A further object is the provision of a totalizer having aligned and independently movable totalizer units operatively connected with each other in a novel manner that at predetermined intervals of their rotation in either direction, one of the totalizer units will effect the positioning of the adjacent totalizer unit.

A still further object is the provision of a totalizer adapted to be bodily carried in a path for engagement with a plurality of rack bars that determine their rotating movements and detent means arranged for yieldingly retaining the units of the totalizer in the position to which they have been advanced while either in or out of engagement with the rack bars.

With the foregoing and other objects in view, the present invention resides in the novel combination and arrangements of parts and in the details of construction hereinafter described and claimed, it being understood that changes in the precise embodiment of the invention herein disclosed can be made without departing from the spirit of the invention.

Referring to the drawings:

Figure 1 is a view of an adding machine embodying my improvements and is partly in section taken on the line 1—1 of Fig. 2, illustrating a portion of the keyboard in elevation.

Figure 2 is a medial longitudinal sectional view taken on the line 2—2 of Fig. 1.

Figure 3 is a medial longitudinal sectional view similar to Fig. 2 showing a changed position with one of the digit keys depressed and serving as a stop for the advanced type bar in that bank.

Figure 4 is a longitudinal sectional view taken on the line 4—4 of Fig. 1 showing the casing of the machine in section and illustrating the signal keys and the control means for the totalizer.

Figure 5 is an enlarged longitudinal detail sectional view taken on the line 5—5 of Fig. 1 showing the totalizer and associated parts in their normal at-rest position with respect to the first type bar of lowest denominational order.

Figure 6 is an enlarged longitudinal detail sec-

tional view taken on the line 6—6 of Fig. 1, showing the totalizer and associated parts in their normal at-rest position with respect to the second type bar.

Figure 7 is an enlarged longitudinal detail sectional view similar to Fig. 6 showing the totalizer in meshing engagement with the type bars and with the actuator shaft of the adding machine as having been rocked to nearly its entire distance in one direction and also illustrating shaft 150 as having been carried with the actuator shaft to rock the depending arms 154.

Figure 8 is an enlarged partial detail sectional view taken through the totalizer and the type bars substantially on the line 8—8 of Fig. 6.

Figure 9 is a perspective view of the type bar with the parts carried thereon and associated parts coacting therewith.

Figure 10 is a perspective view similar to Figure 9 illustrating the parts carried on the type bar in changed position.

Figure 11 is a perspective view similar to Figure 10 illustrating the parts carried on the type bar and their coacting parts in changed position.

The present application is a division of my prior application, Serial No. 717,156, filed March 24, 1934, for improvements in adding and recording machines, and only so much of the machine shown and described in said application as is necessary for a full understanding of the subject matter claimed in this divisional application will be shown and described. Insofar as it has been possible to do so, the reference numerals appearing in the prior application have been employed to designate the corresponding parts herein.

To more clearly understand the operation of the transfer mechanism, I have explained in general the construction and operation of parts controlled by the digit keys for withholding and releasing type bars which actuate the rotating movements of the units of the totalizer that control and which in turn are controlled by the transfer mechanism.

The numeral 28 designates the bottom wall of the adding machine to which a pair of side plates 29 and 30 respectively are secured and on which the working parts of the machine are supported.

A keyboard having a group of digit keys 31 supported in rows or banks therein, is positioned between the side plates 29 and 30 and the keys are each provided with stems 33 which have their lower end portions 33a serving as stops for controlling the movements of reciprocating type bars 75 when the keys are depressed. These keys are also aligned transversely and their stems 33 are each provided with a vertical slot opening 34 therein through which a shaft 32 extends for limiting its movement in either direction and each key is normally urged upwardly by means of a compression spring 35. The key stems 33

extend through slot openings 38a and 39a, respectively, in a top member 38 and a bottom member 39 of the keyboard. The key stems 33 are each provided on their forward edges with a cam surface 36 and a shoulder 37 which serve, upon the depression of a key, to move and lock a pair of slide members 40 and 48 which are carried on the bottom member 39 below each bank of keys. The slide members 40 and 48 are each provided with a plurality of slot openings 41 and 49 respectively through which the lower ends 33a of the key stems 33 extend. The slides 40 and 48 are arranged for sliding movements on a plurality of studs 42, 43, 44 and 45 fixed to the bottom member 39 and are yieldingly held for movement in one direction against the tension of the springs 46 and 50, respectively, secured to the studs 47 and 57 of the respective slides and to the fixed studs 45 and 44 on the lower member 39.

A plurality of slide locks 54 are carried on a transversely extending shaft 55 carried at the rearward end of the keyboard and these slide locks are each arranged for movement with a slide 40 and are adapted to be rocked into the path of a transversely extending bar 205 which is actuated by the driving mechanism of the adding machine for locking the slides 40 in either their normal or changed positions.

Zero stops 58 are supported for free rocking movements on a transversely extending shaft 59 carried at the forward end of the keyboard and are for the purpose of selectively limiting the movement of the type bars to permit the zeros thereof to be automatically positioned in a printing line. A type bar stop 65 which is provided with a depending portion 66 is also carried on the shaft 59 adjacent each of the zero stops 58 and is controlled by the movements of the zero stop 58 with the depending portion 66 thereof normally in the path of the ear 76 on the coacting type bar 75. The type bar stops 65 are each provided with an angular formation 69 that projects over a forwardly extending portion 64 of the zero stop 58 and under an extending portion 70 of a type bar stop 65 in the adjacent bank of lower denominational order. The movement of a lower slide 48 caused by depressing a digit key 31 will rock the zero stop 58 on the shaft 59 and cause the extension 64 thereof to engage the angular formation 69 of the type bar stop 65 and the angular formation 69 will also engage the extension 70 of the adjacent type bar stop 65 in the bank of lower denominational order and position the depending portion 66 thereof free of the ear 76 of the coacting type bar 75.

The type bar stops 65 are yieldingly carried with the zero stops 58 against the tension of a spring 73 which is fixed to an inwardly extending ear 73a on the type bar stops and to a pin 74 fixed in a partition wall 71 that extends between each of these units and which also serves as a spacer therefor.

Type bars

The type bars 75 are each provided at their forward ends with an ear 76 which is adapted to be engaged by the depending portion 66 of the type bar stop or by the depending portion 63 of the zero stop. Each of the type bars is provided on its top edge with a plurality of steps 71 forming stops which are adapted to be engaged by the end 33a of one of the selected depressed digit keys 31. A type bar 75 is arranged for sliding movements below each row of digit keys 31 on a transversely disposed shaft 78 that extends

through an elongated slot opening 79 in the type bars and is fixed in the side plates 29 and 30. The type bars 75 are also guided at their rearward end portions in the combs 81 and 83 which are also fixed to the side plates 29 and 30. 5

A full and complete description of the keyboard and its operation has been given in my application, Serial No. 751,812, filed November 7, 1934, and it is thought that a brief description of the operating parts coacting with the type bars 10 forming a part of this invention will suffice.

Each of the type bars 75 is provided with a long and relatively narrow slot opening 84 which serves to guide a driving rack 85 thereon by means of the studs 86 and 87 secured to the rack 15 and extending through the slot opening 84. The rack 85 is normally urged toward the front end 84a of the slot opening 84 by means of a relatively long tension spring 88 which has one end secured thereto and its other end secured to a pin 20 89 on the type bar. The racks 85 are each in constant meshing engagement with a rack gear 90 fixed to a shaft 91 that is journaled in the side plates 29 and 30 below the type bars 75. The shaft 91 extends outwardly of the side plate 30 25 and has a driving gear 92 fixed thereto which is adapted to be engaged by a segmental gear 93 (Figs. 1, 2 and 7), which is fixed to a rockable actuator shaft 94 that is positioned below the shaft 91 and which is also journaled in the side 30 plates 29 and 30. A geneva type of lock 96 is fixed to the shaft 91 adjacent the gear 92 and is adapted to cooperate with a geneva locking member 97 which is fixed to the actuator shaft 94 to retain the shaft 91 locked against turning movements at each limit stroke of the rockable actuator shaft 94. The geneva locking member 97 is provided with dwells 98 and 99, respectively, at each peripheral end thereof which dwells coact with the convex surfaces 100 and 101, respectively, formed on the edge of the geneva lock 96 which provide a space between the dwells 98 and 99 which permits of the free rotating movement of the geneva lock 96 and the rotation of the gear 92 with the segment 93 which is brought into meshing engagement with this gear 92 as the actuator shaft 94 is rocked.

The type bars 75 are each provided with an ear 161, (Figs. 2, 5 and 6), which is adapted to be normally engaged by means of a type bar lock arm 160 that is pivotally mounted on the shaft 107 and has an integral depending arm 154 that is normally retained in the path of movement of a shaft 150 by means of a spring 156 fixed thereto and to a cross member 157 fixed to the side plates 29 and 30. The shaft 150 is bodily carried for rocking movements with the actuator shaft 94 in the geneva locking member 97 and in a sector 311. As the actuator shaft 94 is rocked forwardly or to the left, as viewed in the drawings, the shaft 150 will engage the depending arms 154 and effect a swinging movement thereof on the shaft 107 and release the arms 160 from the ears 161 of the type bars and permit the type bars to be driven with the actuator shaft until arrested by a depressed key.

When a key is depressed, the slides 40 and 48 coacting therewith will be caused to move forwardly by means of the cam surface 36 of the key stem 33 engaging the slot openings 41 and 49, respectively, of the slides, and the slide 48 will rock the zero stop 58, which, in turn, will rock the type bar stop 65 with the depending end 66 thereof, free of the ear 76 on the type bar 75 and render the type bar free to be driven as the actuator shaft 94 is rocked.

Totalizer or accumulator

The type bars 75 are each provided with rack teeth 102 which extend partially along the lower edge thereof and which are each adapted to be engaged by a unit of the totalizer A positioned below the type bars. The totalizer A is carried on a pair of arms 103 and 104, respectively, which are pivotally supported for rocking movements on the shaft 91 adjacent each of the side plates 29 and 30. The free ends of the arms 103 and 104 are each connected to a regulating device 109 carried adjacent thereto in fixed position on a shaft 105 that is journaled in the side plates 29 and 30.

15 The shafts marked 106, 107 and 108 are carried in the side plates 29 and 30 and support mechanism extending into the path of movement of the totalizer units A for engagement therewith in either direction of the rocking movements of the arms 103 and 104, and in either direction of their movement, the units A will be positioned into the path of one or the other of the engaging members carried on the shafts 107 and 108, respectively.

20 The totalizer or accumulator units A are rotatably mounted on a shaft 110 carried on the arms 103 and 104, and these units are each provided with a square bushing 111 which has a bore 111a through which the shaft 110 extends. The square portion of the bushing serves as a key on which a gear 112, a total stop disc 113, a detent wheel 114, and a type bar release disc 115 which is provided with a notch 116 on its periphery are secured in spaced relation with each other on this bushing 111 by means of spacing washers 117 and are securely retained as a unit thereon by means of the flanges 118. The units are mounted in spaced relation on the shaft 110 by means of spacing collars 119 and the gear 112 of each unit is aligned for meshing engagement with the rack teeth 102 of each of the type bars 75.

25 When the machine is conditioned for adding operations, and the actuator shaft 94 is rocked forwardly, it will carry an ear 314 of a sector 311 therewith, (Fig. 4), and at near the limit movement of the actuator shaft, the ear 314 will engage a shoulder 313 of a control arm 308 carried on a control member 301 and force the control arm and control member forwardly. The control member 301 being attached to the regulating device at 302, will carry the same forwardly therewith and effect engagement of the totalizer units with the type bars. Upon the restoring movement of the actuator shaft 94, the totalizer units will remain in engagement with the type bars and the restoring movement of the type bars will run into the totalizer, the amount set up in the keyboard. As the actuator shaft 94 nears the end of its restoring movement, a pin 310 on the sector 311 will engage a bifurcated portion 312 of the control arm 308 and restore the same and control member 301, and effect the disengagement of the totalizer from the type bars.

30 The total stop disc 113 of each of the totalizer units is provided with a peripheral lug 120 and is also provided with substantially diametrically opposed studs or pins 121 and 122, respectively, which are secured on opposite faces of the disc. The pins 121 and 122 are for the purpose of tripping mechanism which coacts with the totalizer or accumulator units for effecting a release of the actuating mechanism that controls the adjacent totalizer or accumulator unit of higher order. The pin 122 is adapted to engage a slide

35 release cam 123 (Figs. 7 and 8) on an over-hang-

ing arcuate arm 124 of a rockable member 125 pivotally supported on the shaft 107 and the pin 121 is adapted to engage a cam surface 126 of an arm 127 which is pivotally supported on the transversely extending shaft 108. This arm 127 is in the form of a bell-crank with its other leg portion 128 connected to the rockable member 125 by a pin 129 fixed thereto which extends through an elongated slot opening 130 in the rockable member 125 and forms a toggle action 10 as one or the other of the arms 124 or 127 are caused to be rocked.

40 The rockable member 125 is provided with an extending bent-over portion 131 which is adapted to be engaged by the extending end 132 of a slide member 133 which is carried on an adjacent driving rack 85 of higher denominational order. The slide 133 is arranged for independent sliding movement on the studs 86 and 87 by means of relatively short slot openings 134 and 135 near each end thereof (Figs. 2, 3 and 6), through which the studs extend to support and guide the same in its sliding movements on the type bars. The slide 133 is normally urged toward the front of the machine by means of a tension spring 136 which has one end fixed thereto and with its other end fixed to a link 137 which is also mounted for sliding movement on the stud 86. The stud 86 extends through a relatively short slot opening 138 in the link and is normally aligned with the slot 134 of the slide. The forward end of the link 137 is supported and guided in a relatively long slot opening 139 in the type bar 75 by means of a pin 140 fixed thereto and which extends through this slot opening 139 and is adapted to be carried with the driving rack 85 upon each operating stroke of the actuator shaft 94 of the machine.

45 As thus far described, it will be noted that when the actuator shaft 94 is in its normal at-rest position (Figs. 2 and 5), the dwell 98 of the geneva lock retains the driving gears 90 in locked position which in turn retain the driving racks 85 in their normal at-rest positions and the slide members 133 are yieldingly retained 45 by the tension of their springs 136 against the extensions 131 of the rockable members 125. The operating movement of the actuator shaft 94 will carry the shaft 150 therewith to engage and rock the arms 154—160 to release them from 50 the type bars and will cause the driving racks 85 to be freely moved until the studs 86 and 87 have reached the ends of the slot openings 134 and 135 in the slide members 133 at which time these slide members 133 will be carried with the driving racks 85. The links 137 will also be carried with the driving racks 85 and the extensions 141 of the links will engage the ends 124a of the arcuate arms 124 on the rockable member, preventing a further movement of the links 137, 60 and at this time the driving racks 85 will be permitted to move in advance thereof by means of the yielding tension of the springs 136 attached to the links 137 and to the slide members 133.

65 During this movement of the actuator shaft 94, all of the type bars in the banks in which a key has been depressed will be released and permitted to move with the driving racks 85 until one of the steps 77 of each of the released type bars engages the lower end 33a of a coacting depressed 70 key, which will withhold the racks from further movement. All of the remaining type bars in the banks of higher order in which a key has not been depressed will be retained in locked position by means of the type bar stops 65, but 75

the driving racks 85 thereof will be moved in advance thereof against the tension of their springs 88. The type bars in the banks of lower order of those in which a key has been depressed will be released from their type bar stops 65 by means of the type bar stops of higher order controlling the positioning of the type bar stops of lower order upon their movement while permitting the zero stops in the banks of lower order of the keys depressed to remain in the path of the type bars, so that as the machine is operated, these type bars will be permitted to move until arrested by the zero stops and position the zeros thereof in the printing line.

16 The movement of the actuator shaft 94 will effect the positioning of the units of the totalizer A into meshing engagement with the rack teeth 102 of the type bars 75 prior to their reverse movements to run into these totalizers the amounts set up on the keyboard when adding. During total and subtotal operations, the totalizer units are brought in mesh with the type bars prior to their forward movement. The depression of the total key 211 or the depression of the subtotal key 212 effects a turning movement of the shaft 150 to present a flattened portion thereof aligned with arms 154 so that the rocking movements of the actuator shaft 94 will carry shaft 150 therewith and free of the arms 154. At this time, should some of the units of the totalizer be in zero position while carried into engagement with the type bars, the notches 116 of the type bar release discs 115 will each receive a stud 162 fixed to the type bar lock arms 160, and those totalizer units that are rotated upon the restoring movement of the type bars, will cause the studs 162 to ride out of the notches 116, to release the coating type bar lock arms 160 from the type bars. If the totalizer units have been rotated during a previous operation, the peripheries of the discs 115 will then engage the studs 162 and release the arms 160 prior to the movements of the type bars. The rocking movement of the arms 160 will carry the integral depending arms 154 therewith, and as these depending arms 154 are each provided with an extension 154a that engages the adjacent arm 154 of higher order for movement therewith, the movement of one of the arms 154-160 will effect movement of all of them of lower order thereof. All the arms 154 of higher order of those moved, will remain in their normal positions to retain the type bars of higher order locked against movement.

55 The arms 103 and 104 supporting the totalizer units, also carry a shaft 172 that has a plurality of detent pawls 170 thereon, which each have a relatively wide V-shaped portion 171 that engages a detent wheel 114 of each of the totalizer units, and these pawls are each urged into engagement with its detent wheel by a tension spring 173 secured thereto and to a tie member 95 secured to the arms 103 and 104. These springs 173 yieldingly retain the detent wheels 114 to retain the units of the totalizer from turning movements while permitting them to be rotated by the type bars while in engagement therewith, and the detent pawls 170 also permit the totalizer units to be rotated by a carry over mechanism which will be later described.

During adding operations, the type bars that have been released, as above described, will be carried rearwardly by means of the driving mechanism which carries the driving racks 85 rearwardly, and by means of the springs 88 the

type bars are carried therewith until arrested by the depressed keys. The rearward movement of the driving racks 85 will carry the links 137 therewith by their springs 136. When the type bars are at their limit rearward movement, the totalizer units are carried into engagement with the rack teeth 102 thereof, and prior to the restoring movement of the type bars, the driving racks 85 will be carried in the slots 84 of the type bars until the studs 86 of the driving racks engage the ends 84a of the slots and positively restore the type bars therewith. During the restoring movements of the type bars, the totalizer units will be rotated in a counter-clockwise direction until the ends 102a of the rack teeth 102 have passed the gears 112 of the totalizer units, (Fig. 6), and at which time the totalizer units will be retained in the position to which they have been rotated by the detent pawls 170. Just as the ends 102a of the rack teeth 102 on the type bars are leaving the totalizer units, the extending ends 132 of the slides 133 will engage the bent-over portions 131 of the rockable members 125 and prevent further movement of the slides, while permitting the type bars to be driven by the racks 85 to their at-rest positions. During the movement of the driving racks 85 in advance of the slides 133, the studs 86 of the driving racks will engage the ends of the slot openings 138 in the links 137 and carry them therewith against the tension of their springs 136 and urge the extending ends 132 of the slides 133 against the bent-over portions 131 of the rockable members 125. Each of the slides 133 carries a pin 174a on which a pawl or carrying member 174 is mounted and which pawl or carrying member has a tooth-engaging end 175, and is limited in its movements on the slide 133 by means of a pin 177 extending through a slot 178 in the pawl or carrying member, which is normally urged by means of a spring 176 with the tooth-engaging end 175 readily engageable with the gear 112 of the coacting totalizer unit.

Carry over mechanism

It will be noted that during adding operations, the type bars are moved rearwardly until arrested by the ends 33a of the keys 31 engaging the steps 77 thereof, and at this time, the totalizer units are brought into engagement with the teeth 102 of the type bars, and, during the restoring movements of the type bars, the totalizer units will be rotated to extents equal to the distances of movement of the type bars. The totalizer units are rotated from their point of engagement with the rack teeth 102 to the end 102a of the teeth and should a pin 122 of the total stop disc 113 of one of the rotated totalizer units engage the cam 123 on the arm 124 of the rockable member 125, it will rock this member 125 clockwise with the bent-over portion 131 thereof out of the path of the extending end 132 of the slide 133, and permit this slide to be instantly urged forwardly by its spring 136 with the tooth-engaging end 175 of the pawl or carrying member 174 on the slide, into engagement with the gear 112 of the coating totalizer unit in the adjacent bank of higher order, and rotate the same $\frac{1}{6}$ of a turn.

If an amount has been previously stored up in the totalizer units, and an amount is added thereto and should a pin 122 of one of the totalizer units engage the cam 123 of the rockable member 125, it will rock this member 125 in a clockwise direction prior to the time that the

slide has reached it, and the slide will then pass over the bent-over portion 131 of the rockable member 125 and carry the pawl or carrying member 174 therewith to engage and rotate the totalizer unit $\frac{1}{8}$ of a turn after the ends 102a of the rack teeth 102 have passed the totalizer units. It will be noted that when the bent-over portion 131 of the rockable member is in the path of movement of the slide 133, the driving rack 85 and link 137 are moved in advance thereof, and the link 137 will tension the spring 136 to urge the slide 133 against the rockable member 125 prior to the tripping thereof. When the rockable member 125 has been tripped prior to the time that the slide 133 has reached it, this slide 133 will then pass over the rockable member. Whether the rockable member 125 is tripped while the slide 133 is urged thereagainst or prior to the time that the slide 133 reaches it, the pawl or carrying member 174 on the slide will effect a rotation of the coating totalizer unit of $\frac{1}{8}$ of a turn.

While the totalizer units are in engagement with the type bars, (Figs. 3 and 7), the rotating movement of the totalizer unit will cause the pin 122 to engage the cam 123 and rock the member 124 in the manner as above described, or the pin 121 will engage the cam 126 of the arm 127 to rock the member 125 as the totalizer units are being restored out of mesh with the type bars.

To retain the rockable members in their normal and tripped positions, (Figs. 6 and 7), they are each provided with a bifurcated portion forming legs 142 and 148, that straddle the shaft 108 with the leg 142 provided with a notched-out portion 143 that is adapted to be engaged by a notched-out portion 146 on the free end of an arm 144 pivotally supported on a shaft 145. The arm 144 is normally urged upwardly by means of a tension spring 147 connected thereto and to the leg 148 of the rockable member 125 and retains the leg 142 and the arm 144 readily disengageable with each other and forms a locking device to retain the bent-over portion 131 of the rockable member 125 into or out of the path of the extending end 132 of the slide member 133. The arm 144 is provided with a downwardly directed extension 149 which is adapted to be engaged by the shaft 150 that is bodily carried for rocking movement with the actuator shaft 94, and when engaged, the arm 144 is rocked downwardly with the notched-out portion 146 thereof in engagement with the lower extremity 142a of the leg 142 to retain the rockable member 125 in locked position with the bent-over portion 131 thereof in the path of the adjacent slide 133 of higher order.

During subtraction operations, (Figs. 3 and 7), the totalizer units are brought into engagement with the type bars prior to their rearward movement and as the type bars are moved, the totalizer units will be rotated in a clockwise direction. The type bars are moved until arrested by the depressed keys in the same manner as when adding, but the totalizer units remain in engagement therewith until the type bars are arrested, and at which time, they are carried out of engagement therewith. As the actuator shaft 94 is rocked to effect the rearward movement of the type bars, the driving racks 85, slides 133 and links 137 are carried rearwardly, and the extensions 141 of the links 137 engage the ends 124a of the arms 124 of the rockable members 125 and limit the rearward movements of the links 137. As the driving racks 85 are car-

ried their entire distances rearwardly upon each operation of the actuator shaft 94, it will be seen that when the extensions 141 of the links 137 engage the ends 124a of the arms 124, the springs 136 will permit of a further movement of the driving racks 85 with the studs 86 and 87 thereof riding in the slots 134 and 135 of the slides, and exert a tension on the links 137. Should a carry over occur during these subtraction operations, the pin 122 will engage the cam 123 on the arm 124 of the rockable member 125, and rock this member in the same manner as when adding, but in this instance, the movement of the rockable member will carry the end 124a of the arm 124 thereof out of engagement with the extension 141 of the coating link 137 and permit this link to be urged rearwardly by its spring 136 the distance of the length of its slot 138. This movement of the link 137 will cause the stud 140 thereon to engage an arm 179 pivoted on the shaft 172. This arm 179 of which there is one for each totalizer unit, has a spring 173 fixed thereto at its lower end and to the cross member 95, and carries a pin 179a at its upper end on which a pawl or carrying member 180 is pivotally mounted, and which is provided with a stop 181 that is urged against the arm 179 by means of a spring 182. The pawl or carrying member 180 is normally retained out of engagement with the gear 112 of the totalizer unit by means of the spring 173 on the arm 179, and as the links 137 are carried rearwardly, as above described, the studs 140 thereon will be brought into engagement with these arms 179, but will not effect movement thereof by reason of the extensions 137 of these links engaging the ends 124a of the rockable members. As a pin 122 of a totalizer unit engages the cam 123 to rock the rockable member 125, the end 124a of the arm 124 thereof will be moved out of the path of the extension 141 of the coating link and permit this link to be instantly urged rearwardly by its spring 136, and the stud 140 of the link will effect a clockwise rocking movement of the arm 179 to engage the pawl or carrying member 180 with the gear 112 of the totalizer unit. This engagement of the pawl or carrying member 180 with the gear 112 of the totalizer unit takes place at near the limit rearward movement of the driving racks 85, which permits of the complete setting up of the type bars and rotation of the totalizer units prior to the time that the link 137 is released from the rockable member 125, so that the carry over movement of the totalizer unit will occur and rotate the adjacent unit of lower order $\frac{1}{8}$ of a turn. The rockable member 125 is retained in the position to which it has been rocked by means of the arm 144 engaging the leg 142 thereof and as the actuator shaft is restored to its normal position, the shaft 150 carried therewith will engage and rock the arm 144 and permit the rockable member 125 to be spring-urged by the spring 147 to normal position. The total stop disc 113 of each of the totalizer units is provided with a peripheral lug 120 which is adapted to be engaged by a hook-like portion 164 of a total stop arm 163 that is mounted for rocking movement on the shaft 106 and aligned with a totalizer unit, and which arms are normally retained out of the path of the lugs 120. The lower portions of the total stop arms 163 are each provided with an extension 165 which rests on a floating transversely extending shaft 166 carried for bodily movement on the shaft 106 by means of links 167. Each total stop arm 163 is yieldingly retained with its 75

extension 165 in contact with the shaft 166 by means of a torsion spring 168 which has its body portion encircling the shaft 166 and with its free ends engaging the shaft 166 and the extension 163a of the arm 163 to permit of an independent yieldable rocking action of each of the arms 163.

It will be noted that a total stop arm 163 contacts with the lug 120 of a total stop disc 113 of each totalizer unit, but these total stop arms do not move therewith as the totalizer units are moved into and out of meshing engagement with the rack teeth 102 of the type bars 75, but are arranged to coact with the totalizer in either their normal or raised positions.

15 I claim:

1. In a machine of the character described, the combination of a totalizer unit, an actuator therefor, a pair of carrying members for the totalizer unit, a slide including yieldable means operatively connecting one of the pair of carrying members with the actuator, a link having means thereon for engaging the other of said pair of carrying members including yieldable means connecting the slide and link, a rockable member between said slide and means on said link and engageable thereby in each direction of movement of the actuator, said first-mentioned yieldable means serving to urge one of said pair of carrying members against the rockable member preparatory to a carry during the restoring movement of said actuator, and the second-mentioned yieldable means serving to urge the other of said pair of carrying members against the rockable member preparatory to a carry at near the outward movement of said actuators, said rockable member being rocked by a totalizer unit of lower order to release said slide or link for effecting a carry.

2. The combination of totalizer units and actuators therefor, a spring-impelled slide including a link slidably carried on each actuator, a carrying member on said slide engageable with a totalizer unit upon one direction of movement of the actuator, a second carrying member engageable by the link upon the other direction of movement of the actuator, a rockable member in the path of movement of the slide and link restricting their movement with the actuator and preventing their engagement with the totalizer unit, said rockable member being rocked by an adjacent totalizer unit out of the path of the slide and link for an unrestricted movement of said slide and link to effect a carry in either direction of movement of the actuator.

3. In an adding and recording machine, the combination of a pair of totalizer units and actuators therefor, transfer mechanism comprising a spring-impelled slide and a link carried on each actuator, a carrying member on said slide, a carrying member engageable by said link, said pair of carrying members operable by the slide and link respectively at each limit stroke of the actuator to effect a carry, spring means connecting the slide and link together and with the actuator and tensionable at each limit movement of the actuator urging the carrying members for a carry, a rockable means controlling the movement of said slide and link to control the engagement of the pair of carrying members with their respective totalizer unit, and means connecting the rockable means with a totalizer unit whereby

at certain positions of rotation of the totalizer unit said rockable means will be free of the slide and link and permit the engagement of one of said carrying members with a totalizer unit to effect the carry.

4. In an adding machine of the character described, the combination of totalizer units and actuators therefor, a driving mechanism, a spring-impelled slide carried on each actuator, a carrying member movable with each slide, a second carrying member, a link slidably carried on the actuator for movement with the spring-impelled slide and having means thereon for engaging to move said second carrying member, and a rockable member movable under the control of a totalizer unit and normally positioned between said slide and the means on said link for limiting the movement of said slide and link upon movement of the actuator and preventing engagement of the said first carrying member with a coacting totalizer unit, and spring means to cause a yieldable tension on one or the other of said carrying members at each limit movement of the actuator, and means connecting the rockable member with a totalizer unit whereby to move said rockable member at certain positions of said totalizer unit to release a carrying member to effect a carry.

5. In an adding and recording machine, the combination with a totalizer unit and actuator therefor, a pair of carrying members for each of the totalizer units, a spring-impelled slide on the actuator supporting one of said carrying members, a spring-impelled link including means on the actuator for engaging to move the other of said carrying members, one of said carrying members being urged to engage and turn the totalizer unit at each limit stroke of the actuator, a rockable member between the slide and said means on the link controlling their movements and the engagement of the carrying members with a totalizer unit, and means on said rockable member extending into the path of an adjacent totalizer unit and engageable thereby for effecting the movement of the rockable member to release said slide and link for a spring-impelled movement to effect a carry.

6. In a machine of the character described, the combination of totalizer units, actuators therefor, a pair of carrying members for each totalizer unit, a slide on the actuator, a link including a pin on the actuator, one of said carrying members being carried by the slide and the other of said carrying members being positioned by said pin on the link, yieldable means connecting said slide and link together and with the actuator, said slide and link being movable by said yielding means to move their respective carrying members, rockable means limiting movement of said slide and first-mentioned carrying member in one direction of movement of the actuator and limiting movement of said link in the other direction of movement of the actuator, said rockable means being rocked in certain positions of turning movements of a totalizer unit for rendering said slide and link free thereof to permit the carry, the carrying members effecting the carry in the direction of movement of the actuator.

MAX GARBELL.
